(57) CLAIM

The ornamental design for a bottle, as shown and described.

DESCRIPTION

FIG. 1 is a top, front, right side perspective view of a bottle; FIG. 2 is a front elevation view thereof; FIG. 3 is a rear elevation view thereof; FIG. 4 is a left side elevation view thereof; FIG. 5 is a right side elevation view thereof; FIG. 6 is a top plan view thereof; and, FIG. 7 is a bottom plan view thereof.

The bottle is shown with a symbolic break in its length. The appearance of any portion of the article between the break lines forms no part of the claimed design. The long-dash short-dash boundary lines represent boundaries of the claimed design and form no part thereof. All other broken lines illustrate portions of the bottle that form no part of the claimed design
